(57) **CLAIM**

I claim the ornamental design for a fluid container, as shown and described.

DESCRIPTION

FIG. 1 is a perspective view of a fluid container showing the top, rear, and left sides of my design;

FIG. 2 is a perspective view thereof showing the top, front, and right sides of my design;

FIG. 3 is a perspective view thereof showing the bottom, rear, and left sides of my design;

FIG. 4 is a right side elevational view thereof, the left side being a mirror image thereof;

FIG. 5 is a front elevational view thereof;

FIG. 6 is a rear elevational view thereof;

FIG. 7 is a top plan view thereof; and,

FIG. 8 is a bottom plan view thereof.

The broken lines shown in the drawings illustrate portions of the fluid container that form no part of the claimed design. The broken lines on the middle of the fluid container depict symbolic break lines. Any appearance of the container between the break lines form no part of the claimed design.
